UNITED STATES PATENT OFFICE.

GEORGE P. FITZSIMMONS, OF NEWARK, NEW JERSEY.

PACKAGE OR BOX TIE OR FASTENER.

1,177,096.

Specification of Letters Patent.

Patented Mar. 28, 1916.

Application filed April 19, 1915. Serial No. 22,346.

To all whom it may concern:

Be it known that I, GEORGE P. FITZSIMMONS, a citizen of the United States, residing at Newark, in the county of Essex and State of New Jersey, have invented certain new and useful Improvements in Package or Box Ties or Fasteners; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in cord or twine-fasteners or clips, serving as tie-clips for positively binding or fastening the crossed or twisted portions of cord or twine employed for securing wrappers about packages or boxes; and, the present invention has reference more particularly, to a novel cord or twine fastener or clip of the general character hereinafter more fully set forth, which is readily applied in its secured relation to the crossed or twisted portion of a piece of twine or cord arranged around the wrapper of a package or box, to avoid tying or knotting of the cord or twine.

The present invention has for its principal object to provide a cord or twine-fastener or clip of the character and for the purposes stated, which is of a simple construction, is easily applied, is of a cheap manufacture, and positively prevents the cord or twine from becoming untied or from slipping from its surrounding relation with the package or box.

Other objects of this invention not at this time more particularly enumerated will be clearly understood from the following detailed description of the present invention.

With the various objects of the present invention in view, the invention consists, primarily, in the novel construction of cord or twine-fastener or clip of the general character hereinafter set forth, which permits of the fastening of a package or box after the same has been bound with cord or twine without the necessity of knotting the cord or twine.

The invention is clearly illustrated in the accompanying drawings, in which:

Figure 1 is a top or plan view of the

crossed portions of a piece of cord or twine, and of the novel fastener or clip in clamped or fastened relation thereto; Fig. 2 is a rear view of the same; and Fig. 3 is a vertical section, taken on line 3—3 in said Fig. 1, looking in the direction of the arrow *x*, and showing the fastener or clip in side elevation. Fig. 4 is a plan of a blank from which the said fastener or clip is made. Fig. 5 is an end elevation of the said fastener or clip; Fig. 6 is a central longitudinal vertical section of the same; and Fig. 7 is a transverse vertical section, said section being taken on line 7—7 in said Fig. 6, looking in the direction of the arrow *y*. Fig. 8 is a top or plan view of the twisted portions of a piece of cord or twine, and of the novel fastener or clip in clamped or fastened relation thereto; and Fig. 9 is a rear view of said fastener or clip. Fig. 10 is a vertical sectional representation, similar to that represented in said Fig. 3, but showing in side elevation a fastener or clip of a modified construction; and Fig. 11 is a plan of a blank from which the form of clip or fastener represented in said Fig. 10 is made.

Similar characters of reference are employed in all of the said above described views, to indicate corresponding parts.

Referring now to the several figures of the drawings, the reference-characters 1 and 2, in Figs. 1, 2, 3 and 10 indicate the crossed portions of a piece of cord or twine, when bound about a package or box; and the reference-characters 3 and 4 indicate the usual twisted portions of a piece of cord or twine.

The cord or twine-fastener or clip, shown in Figs. 1 to 9 inclusive, and which represents one embodiment of the principles of the present invention, comprise a flat base-plate or body, as 5, of any suitable marginal configuration, from the one edge portion of which extend in an upwardly curved manner, as at 6, a pair of clamping or fastening tongues or fingers, as 7, said tongues or fingers extending forwardly over and above the said base-plate or body 5, substantially as shown. In cross-section, each tongue or finger 7 is also made of a con-

cavo-convex configuration, as indicated more particularly in Fig. 7 of the drawings, so that the respective marginal edges 8 of the said tongues or fingers 7 will provide biting edges for positively gripping the cord or twine, to prevent slipping, substantially as and for the purposes hereinafter more fully

described. At the points or roots where the said tongues or fingers 7 join the marginal edge of the said base-plate or body 5, the said tongues or fingers 7 are also joined by 5 a sharply curved marginal edge, as 9, as shown in Figs. 4, 5 and 7 of the drawings. The said base-plate or body 5 may also be provided with upwardly projecting and laterally extending grasping or biting members, as 10, which, with the fastener or clip to be used with the crossed portions of the cord or twine, lie in vertical planes at right angles to the longitudinal vertical planes of the said tongues or fingers, as shown in 15 Figs. 2 and 4 of the drawings; or with upwardly projecting and longitudinally extending grasping or biting members, as 11, which with the fastener or clip to be used with the twisted portions of the cord or 20 twine, lie in vertical planes parallel to the longitudinal vertical planes of the said tongues or fingers, as will be evident from an inspection of Fig. 9 of the drawings.

In lieu of the general construction of cord 25 or twine fastener or clip herein-above described, the fastener or clip may be made from a blank of the shape indicated in Fig. 11 of the drawings, in which case the reference-character 12 indicates the base-plate or 30 body of the fastener or clip, from the opposite edge-portions of which extend in an upwardly curved manner, as at 13 and 14, clamping or fastening fingers or tongues 15 and 16, said tongues or fingers extending 35 over and above the said base-plate or body, and being of such lengths that the opposite fingers or tongues 15 and 16 can be brought into an overlapped relation, as shown at 17 in Fig. 10 of the drawings. In all other respects, the fingers or tongues 15 and 16 are 40 made in the same manner as the fingers or tongues 7 of the fasteners or clips shown in Figs. 1 to 9 inclusive, and the said base-plate or body 12 is provided with suitably-disposed grasping or biting members, as 18.

The manner of arranging the cord or twine-fasteners or clips herein-above described in their relative positions to the crossed portions or the twisted portions of 50 the cord or twine will be clearly evident from an inspection of the several figures of the drawings, it being understood that normally the clamping or retaining fingers or tongues are sufficiently elevated to readily permit of the placing of the said fasteners or clips in position.

After the fasteners or clips have been placed in position, by means of a proper tool, or otherwise, force is applied to the 60 said fingers or tongues and firmly pressed down upon the crossed portions or the twisted portions of the cord or twine, whereby all parts are positively connected, and any slipping of the cord or twine upon the 65 package or box, or any movement of the fas-

teners or clips, is fully overcome, the various edge-portions 8 of the fingers or tongues, as well as the various grasping or biting members being forced into positive holding or retaining engagement with the respective portions of the cord or twine, as will be clearly evident. 70

Of course, I am fully aware that some changes may be made in the general arrangements and combinations, as well as in the 75 configurations of the several parts, without departing from the scope of the present invention as set forth in the foregoing specification, and as defined in the clauses of the claim which are appended thereto. Hence, 80 I do not limit my invention to the exact arrangements and shapes of the various parts as described in the said specification, nor do I confine myself to the exact details of the 85 construction of the said parts, as illustrated in the accompanying drawings.

I claim:—

1. A package or box tie or fastener comprising a base-plate, upwardly projecting clamping fingers connected with and extending longitudinally above said base-plate for clamping crossed or twisted portions of cord or twine against movement between said base-plate and said fingers, said fingers being of concavo-convex cross-section, whereby 95 the longitudinal marginal edges of the said fingers provide means for biting the cord or twine.

2. A package or box tie or fastener comprising a base-plate, upwardly projecting clamping fingers connected with and extending longitudinally above said base-plate for clamping crossed or twisted portions of cord or twine against movement between said base-plate and said fingers, said fingers being of concavo-convex cross-section, whereby 100 the longitudinal marginal edges of the said fingers provide means for biting the cord or twine, and a grasping or biting member 95 extending upwardly from said base-plate in a direction toward the said fingers and at right angles to the longitudinal axes 105 of said fingers.

3. A package or box tie or fastener comprising a base-plate, a pair of curved clamping fingers connected with and extending upwardly from one of the marginal edges of said base-plate and longitudinally of said base-plate for clamping the crossed portions 110 of cord or twine between said fingers and beneath said fingers against movement between said base-plate and the said fingers, said fingers being of concavo-convex cross-section, whereby 115 the longitudinal marginal edges of the said fingers provide means for biting the cord or twine. 120

4. A package or box tie or fastener comprising a base-plate, a pair of curved clamping fingers connected with and extending upwardly from one of the marginal edges 130

of said base-plate and longitudinally of said base-plate for clamping the crossed portions or cord or twine between said fingers and beneath said fingers against movement between said base-plate and the said fingers, said fingers being of concavo-convex cross-section, whereby the longitudinal marginal edges of the said fingers provide means for biting the cord or twine, and a grasping or biting member extending upwardly from

said base-plate in a direction toward the said fingers and at right angles to the longitudinal axes of said fingers.

In testimony, that I claim the invention set forth above I have hereunto set my hand this 17th day of April, 1915.

GEORGE P. FITZSIMMONS.
